VALVE OPERATOR

Edward C. Ehlike, Milwaukee, Wis., assignor, by mesne assignments, to Controls Company of America, Schiller Park, Ill., a corporation of Delaware

Application December 10, 1954, Serial No. 474,449

1 Claim. (Cl. 236—48)

This invention relates to a valve operating mechanism which has operating characteristics particularly adapting the device to the control of gas flow to a burner.

It is well known that a gas burner requires a greater flow for ignition purposes than is required to sustain combustion after ignition has taken place. In many cases it is desirable to provide a modulating flame at a burner within the limits of the combustion range. Controls affording a modulating flow rate have heretofore been generally characterized by the fact that the low limit of the modulating range was necessarily the flow rate occurring when the operating mechanism opened the valve for ignition purposes. Therefore, the low limit on the modulating range was higher than desirable when considering the modulating portion of the operation alone. The present control apparatus will provide a lower limit for the modulating portion of the operating cycle while providing a high initial flow rate for ignition purposes. Thus, the present unit provides a high flow rate for ignition purposes with a far greater modulating range than found in the prior art devices.

The principal object of this invention is to provide a valve operating mechanism capable of modulating the valve over a wide range while opening the valve for ignition to a high flow position well above the low flow rate encountered in the modulating portion of the operating cycle.

Another object of the present invention is to provide a control of the type described which may be produced at low cost.

Other objects and advantages will be pointed out in, or be apparent from, the specification and claim, as will obvious modifications of the single embodiment shown in the drawing in which the single figure represents a vertical section through a control unit incorporating the present invention.

The device illustrated in the drawing is adapted to be used in connection with other apparatus such as the basic unit shown in application Serial No. 475,174 of Heiser et al., now Patent Number 2,743,871. However, the present device could also be used as a separate control by adapting the inlet and outlet ports for pipe fittings or the like. The control is encased in a split housing 10 having a bottom portion 12 and an upper housing 14. The bottom housing is provided with inlet 16 and flow through outlet 18 is regulated by the series valves 20 and 22; although, as will be pointed out more fully hereinafter, the flow can be regulated by a single valve if desired. Inner or small valve 20 is provided with a short stem 24 having a shoulder or washer 26 limiting the downward movement of the valve with respect to outer or annular valve 22 under influence of light spring 28 by contact with annulus 30 mounted in the outer valve structure. Thus, the light spring 28 urges small valve 20 downwardly to the limit position determined by contact of washer 26 with annulus 30. As shown in the drawing, light spring 28 has been deflected by reason of seating both the small valve and annular valve 22. It

2

will be appreciated that as the large valve moves upwardly, the small valve would remain seated until the lost motion is taken up between the two valve structures whereupon the small valve would be unseated also. The stem of annular valve 22 projects through a cooperating hole in lever 32 and is connected to the lever by coil spring 34 compressed between the lever and washer 36.

The small valve 20 is designed to control the main flow to the outlet 18 and when valve 20 is seated, the major portion of the flow to the outlet is cut off. However, until the annular valve 22 seats a small flow rate can occur by passage between the annular valve 22 and its seat 38 into the annular well 40 and through the small by-pass conduit 42. The low limit of the modulating portion of the operating cycle of this valve mechanism is determined by the seating of valve 20 on its seat 44 while flow continues through the by-pass 42. The "off" position is, of course, determined by seating both valves.

20 Lever 32 which carries both valves is pivotally on pin 46 mounted in housing 10. The lever is provided with a cut-out 48 through which the right-hand end 50 of lever 52 may project to overlie lever 32. Lever 52 is also pivotally mounted on pin 46 and is urged upwardly by compressed spring 54. Lever 32 is yieldably connected to lever 52 by means of spring 56 compressed between the underside of lever 32 and the head of depending adjustable screw 58 threaded into the right end 50 of lever 52. Thus, when the lever 52 tends to move upwardly, the spring 56 would be compressed if the valve lever 32 were restrained from upward movement. The force of spring 56 can be adjusted by adjusting screw 58 and will increase as the degree of compression of the spring is increased as encountered when the levers 52, 32 tend to move apart under the conditions just described.

25 Lever 52 constitutes the control lever in that it receives the control motion from the temperature responsive mechanism. This mechanism is mounted on the upper 40 housing 14 in the tubular portion 60. The temperature responsive mechanism includes a charged bellows assembly including the cylindrical outer casing 62 containing the bellows 64. The casing 62 is adapted for vertical movement within the tubular chamber 60 as will be pointed out more fully hereinafter. Bellows chamber 66 is connected by capillary tube 68 to a charged temperature responsive bulb, not shown. As the temperature at the bulb varies, the pressure within chamber 66 will vary to flex bellows 64. This movement is transmitted to 50 control lever 52 by means of pin 70. The headed upper end of the pin normally seats against shoulder 72 in fitting 74 by reason of the compression of spring 76 between the underside of fitting 74 and washer 78 mounted on the pin. This spring is employed solely to 55 allow overtravel in the event the system is subjected to an abnormally high temperature calling for greater bellows movement than can be had whereupon the spring 76 will collapse to permit the relative movement between the bellows and the pin and prevent damage to the bellows. The top of fitting 74 is sealed by cap 75 soldered to the fitting. It is to be noted that the pin is brought into the inside of housing 10 through the seal 80 to prevent leakage of gas at this point.

60 The capillary tube 68 connects to chamber 66 through the fitting 82 projecting laterally from casing 62 through a slot 84 in the side of the tubular well 60. The bellows assembly is held in position by means of cap or knob 86 threadably mounted on the upper end of the tubular chamber 60 for rotation through approximately 360 degrees determined by engagement of lug 88 with either side of the stop pin 90 mounted on housing 10. Rotation of the knob 86 is employed to determine the operating

characteristics or the maintained temperature of the control. Thus, as the knob is turned from the position shown, the spring 54 acting on the underside of control lever 52 will move the entire bellows assembly upwardly to follow the position of the knob 86. This will, of course, determine the position of the valves also, and, therefore, the temperature at which the valves open and close. It will be noted that the knob is provided with a calibrating screw 92. As thus far described, it will be appreciated that if the bellows pressure is reduced, pin 76 will move upwardly and control lever 52 will follow under the bias of spring 54. This would normally tend to open the valves. However, the valve lever 32 is urged towards the valve closed position by means of spring 94 compressed between seat 96 carried on the adjustable point 98 and 10 seat 100 carried on pin 102 projecting from lug 104 projecting from valve lever 32. Therefore, the spring 94 exerts a force component generally parallel to the axis of the valves and thus tending to seat the valves. This force can be adjusted by adjusting member 98 and the force of 15 the spring is adjusted to be greater than the force of spring 56 when the parts are in the position shown. Therefore, when the control lever 52 moves upwardly, the valve lever 32 will not follow and this results in compressing spring 56 until the increased force of spring 56 20 is greater than the vertical component of spring 94. When this occurs, the spring 56 will act to swing lever 32 upwardly and open both valves to the substantially fully open position. The reason that the valves go to the substantially full open position is that upon the lever 32 25 starting its upward movement the vertical force component of spring 94 steadily decreases and the system acts with a snap action up to the point at which the valve lever contacts the underside of the control lever. As the pressure within the chamber 66 varies now with temperature changes, the two levers will act in unison to achieve a modulating action between the upper and lower ranges of flow. The low range of flow is determined when the small valve 20 seats. At this point, the force of spring 94 is substantially equal to the force of spring 56 and any 30 further downward movement of the control lever will necessarily result in swinging pivot point 102 of spring 94 downwardly to result in a greater vertical force component exerted by spring 94. This will snap the valve 22 shut since the initial movement of lever 32 from this 35 point onwardly results in further increase of the vertical force component of spring 94. Therefore, the valve will open and shut with a snap action with the opening movement being substantially to the full open position and the closing movement occurring from a very low flow 40 rate position.

While the present structure is shown as employing two series valves, the device can be made to operate with only one valve controlling flow through a single port. This 45

will be appreciated since the forces exerted by springs 94 and 56 can be balanced so the single valve would be at its lowest flow position just prior to spring 94 over-balancing spring 56. The present structure permits of slightly greater accuracy in regulating flow and is for that reason preferred.

It will be appreciated that other variations of the present structure can be employed. For instance, the biasing forces need not be springs, but can be any other devices which will vary the exerted force upon changes in spatial relationships of parts. One such device which would be readily suggested would be a magnet which, of course, increases its pull as the pole faces approach. For this reason, the present structure is to be taken as being exemplary only, but not as being a limitation upon the scope of the claim. It will also be appreciated that other temperature responsive devices might be employed in lieu of the bellows system illustrated. The bellows system is preferable in that it is well suited to a modulating action.

Although but one embodiment of the present invention has been illustrated and described, it will be apparent to those skilled in the art that various changes and modifications may be made therein without departing from the spirit of the invention or from the scope of the appended claim.

I claim:

A valve operator comprising, a housing having an inlet and an outlet, a pivot in said housing, a valve lever mounted on said pivot, a valve carried by the lever and adapted to cooperate with the outlet in regulating flow from the casing, temperature responsive means including an element movable in response to temperature variations, a control lever mounted on said pivot and operatively connected to said element so the lever follows movement 30 of the element, a spring connecting the levers to normally cause the levers to move in unison but allowing the valve lever to move toward or remain at the valve closed position independently of the control lever action, said spring exerting an increasing force on the valve lever urging the valve lever towards the control lever as the levers move apart, means for adjusting the force exerted by the spring, a second spring compressed between the valve lever and the housing to exert an increasing force component on the lever in the valve seating direction as the lever moves the valve towards the seat, and means for adjusting the force exerted by said second spring.
